William J. Bohan

By Geo. J. Height
His Atty.

UNITED STATES PATENT OFFICE.

WILLIAM J. BOHAN, OF ST. PAUL, MINNESOTA.

CAR CONSTRUCTION.

Application filed August 13, 1921. Serial No. 491,943.

To all whom it may concern:

Be it known that I, WILLIAM J. BOHAN, a citizen of the United States, residing at St. Paul, in the county of Ramsey and State 5 of Minnesota, have invented a certain new and useful Improvement in Car Constructions, of which the following is a full, clear, concise, and exact description, reference being had to the accompanying drawings, 10 forming a part of this specification.

This invention relates to improvements in car construction.

One object of the invention is to provide a novel combination and arrangement of car 15 underframe and shock absorbing devices for efficiently distributing the shocks to the entire underframe.

Another object of the invention is to provide a novel arrangement of multiple shock 20 absorbing devices, such that, assuming like conditions prevailing, each shock absorbing mechanism may be made of lighter weight and capacity than heretofore and the total capacity of all shock absorbing mechanisms 25 made sufficient to effectively take care of any extreme conditions which may arise in service, particularly in the case of the extremely high capacity cars now being built by many of the railroads.

30 Other objects of the invention will more clearly appear from the description and claims hereinafter following:

In the drawing forming a part of this specification, Figure 1 is a top plan view of 35 a portion of a car underframe with associated shock absorbing devices, embodying my improvements. Part of the underframe construction is broken away or omitted in order to better accommodate the view on the 40 sheet. Figs. 2 and 3 are vertical sectional views corresponding substantially to the section lines 2-2 and 3-3 respectively of Fig. 1.

In carrying out my invention I preferably 45 employ a cast platform or end construction for the underframe, it being understood that this construction will be duplicated at each end of the car and the castings united by suitable center sills, side sills and braced by 50 cross-bearers and needle beams as desired. In the drawing, I have illustrated the casting for one end of the car only, and the same, as shown, comprises an end sill A; a bolster B; side sills C; centrally disposed 55 longitudinally extending draft sills D-D;

and diagonally extending combined braces and draft sills E-E.

The end sill A may be made of any suitable cross-section to conform with the practice of the different railroads, the one shown 60 having upper and lower horizontally extending flanges 11. The end sill is suitably enlarged at the center and has provided a buffering block as indicated at 12. The bolster B, as shown, is of substantially I cross-section with upper and lower flanges and vertical central web, the latter being indicated at 13. The casting is suitably formed at the center of the bolster to provide a bolster center bearing plate as indicated at 14 and 65 an opening 15 for the king pin.

The side sills C, as shown, are of substantially the same cross section as the end sill and united with the latter at the outer ends thereof and also with the bolster at 75 the outer ends thereof.

Inwardly of the bolster proper, the end casting of the underframe is provided with short longitudinally extending webs 16-16 which provide what may be termed stub 80 center sills to which may be united center sills proper 17-17 of channel or other desired form. Side sills extending between the two castings of channel or other cross section as may be desired and indicated at 85 18 may be riveted to the sills C of the castings at the ends of the bolster proper.

The central draft sill portions of the casting are also preferably of channel cross section as best indicated in Fig. 2, the same 90 having webs 19-19 with lower out-turned flanges 20 and upper wider out-turned flanges 21. Suitable integral rear stop lugs are formed on the casting as indicated at 22-22 for the central or main shock absorbing 95 device indicated conventionally at F.

The diagonally extending combined braces and draft sills E-E are also preferably of channel cross section as best indicated in Fig. 3, the same having webs 23, lower 100 flanges 24 and upper flanges 25. As clearly appears from Fig. 1, the innermost webs 23 of the diagonally extending draft sills, merge with the webs 19 of the longitudinally extending draft sills D. The outer webs 23 of 105 the diagonally extending draft sills, at their forward ends, are deflected slightly outwardly for a short distance as indicated at 23^a; are then extended inwardly and transversely for a short distance as indicated at 110

28^b to form front stop lugs, and are then extended longitudinally in line with the central draft sills D and merged with the end sill of the casting, as indicated at 23^c. On 5 the inner faces of each of the diagonally extending draft sills E, at suitable points, are formed integral stop lugs 26—26 with which cooperate the diagonally disposed shock absorbing devices indicated conventionally at G—G. It will be noted that the 10 diagonally extending draft sills E—E are united with the side sills C and bolster substantially at the juncture thereof and may also be said to extend from a point proximate 15 to the juncture of the central draft sills with the end sill. For greater strength and rigidity the diagonally extending draft sills E—E are united along the tops thereof with a web 27 which merges with a corresponding web 28 uniting the tops of the 20 central draft sills D and the top flange of the bolster proper. As best shown in Fig. 3, the bottoms of the diagonally extending draft sills E are also preferably united by horizontally extending web as indicated at 29 for 25 a portion of the length of said diagonally extending draft sills, the remainder being open to permit of the insertion and removal of the shock absorbing devices G—G. The latter are held in operative position by any 30 suitable means such as the saddle plates 30—30 and likewise the centrally disposed shock absorbing device F is held in operative position by a detachable saddle plate 31.

35 As will be understood by those skilled in the art, the end sill A of the platform casting is suitably apertured to accommodate the shank of the draw bar H. The latter is connected with a hooded cast yoke J by 40 means of a detachable coupler key K which extends through suitable slots in the shank of the draw bar, slots in the side walls of the hooded yoke and suitable slots in the web portions 23^c heretofore described. Said 45 yoke J encircles the centrally disposed shock absorbing device F so that the latter is adapted to be operated in both buffing and draft movements of the draw bar as hereinafter described.

50 The shock absorbing devices, F and G indicated conventionally in the drawing, are of that type preferably having a pressure-transmitting wedge at the forward or outer end thereof as indicated at 32 on the central device F and at 33—33 on the diagonally extending shock absorbing devices G. Disposed within the yoke J and extending transversely thereof is a follower, preferably 55 in the form of a hollow casting as indicated at L. The latter is provided on the outer or front portion thereof with a transversely extending wall 34 adapted to be engaged by the inner end of the draw bar shank and to engage the stop shoulders 60 formed by the web portions 23^b heretofore

described. On its inner side said follower L is provided with another transversely extending wall 35 adapted to directly engage the pressure-transmitting wedge 32 of the central shock absorbing device F. At its ends, the follower L is provided with inclined walls 36—36 arranged perpendicular to the central line of the shock absorbing devices G—G. Applied to each of said inclined walls 36 is a detachable wear plate 37 of suitable hardened metal, the thickness of said plates 37 being variable so that by interchanging said plates, compensation may be readily made for wear on the parts. The operative faces of the follower 75 L are obviously adapted to engage and actuate the pressure transmitting elements 33 of the diagonally extending shock absorbing devices G.

The operation is as follows: In buff, the 80 central shock absorbing device F is actuated in the regular manner by means of the follower L. Simultaneously therewith, the diagonally disposed shock absorbing devices G will also be actuated and in this connection it will be noted that friction will 85 be generated between the inclined operative faces of the detachable wear plates 37 and the elements 33 of said diagonal shock absorbing devices G, thus augmenting the capacity of all three shock absorbing devices. In draft, the follower L will obviously be 90 held stationary against the stop shoulders 23^b. The centrally disposed shock absorbing device F will be operated in the usual 95 manner. During draft, however, the diagonally disposed shock absorbing devices G, will not be actuated with the arrangement shown. As is well known to those skilled 100 in the art, the maximum buffing shocks encountered in the service of railroad cars is many times greater than the maximum 105 shocks ever encountered in draft. With my arrangement I am enabled to take care of any unusual or excessive loads which may be encountered in buff and at the same time 110 provide an easy shock absorbing mechanism in draft to facilitate starting of a train of cars.

From the preceding description, it will 115 also be seen that each of the shock absorbing devices F and G may be made lighter and of lesser capacity than any single shock absorbing mechanism which is now employed to take care of equal shocks. It will 120 further be observed that in buffing action, the load transmitted from the draw bar are effectively and efficiently distributed not only to the centrally disposed draft and center sills of the car, but also outwardly 125 to the side sills of the car and to the bolster, and hence, to the entire underframe construction intermediate the bolsters. With this arrangement, an exceedingly 130 strong underframe construction is obtained

with a minimum number of parts; the underframe may be made comparatively light as compared with prior constructions employed with a single shock absorbing device 5 with consequent minimization in the cost of manufacture, up-keep, and transportation charges.

I have herein shown and described what I now consider the preferred manner of 10 carrying out the invention but the same is merely illustrative and I contemplate all changes and modifications that come within the scope of the claims appended hereto.

I claim:

1. In car construction an underframe including: a bolster, an end sill; longitudinally extending centrally disposed draft sills between the end sill and bolster; diagonally extending combined bracing and shock-absorbing-mechanism-supporting sills from said centrally disposed draft sills to the ends of the bolster; and a shock absorbing mechanism supported by each of said diagonally extending supporting sills.

2. In car construction an underframe including: a bolster; an end sill; longitudinally extending centrally disposed draft sills between the end sill and bolster; diagonally extending combined bracing and shock-absorbing-mechanism-supporting sills from said centrally disposed draft sills to the ends of the bolster, all of said sills and bolster being integrally formed; and spaced shock absorbing mechanism supporting members 35 depending from said diagonally extending sills.

3. In car construction an underframe including: a bolster; an end sill; longitudinally extending centrally disposed draft sills between the end sill and bolster; side sills extending between and united to the corresponding ends of the end sill and bolster; diagonally extending, combined bracing and shock-absorbing-mechanism-supporting sills 45 from the centrally disposed draft sills to the ends of the bolster; and means on said diagonally extending sills for receiving the shock absorbing mechanisms.

4. In car construction an underframe including: a bolster; an end sill; longitudinally extending centrally disposed draft sills between the end sill and bolster; side sills extending between and united to the corresponding ends of the end sill and bolster; 55 diagonally extending, combined bracing and shock-absorbing-mechanism-supporting sills from the centrally disposed draft sills to the ends of the bolster, all of said sills and bolster being integrally formed; and spaced members on each of said diagonally extending sills adapted to receive a shock absorbing mechanism therebetween.

5. In car construction, the combination with a centrally disposed longitudinally extending shock absorbing mechanism; of in-

wardly divergently arranged shock absorbing mechanisms, one on each side of said centrally disposed shock absorbing mechanism; means for operating all of said mechanisms from a draw bar; and draft sills for all of 70 said mechanisms.

6. In car construction, the combination with a centrally disposed longitudinally extending shock absorbing mechanism; of inwardly divergently arranged shock absorbing mechanism, one on each side of said centrally disposed shock absorbing mechanisms; means for operating all of said mechanisms simultaneously upon buffing movement of a draw bar; and means for operating only said 80 centrally disposed mechanism upon draft movement of a draw bar.

7. In car construction, the combination with a centrally disposed longitudinally extending shock absorbing mechanism; of inwardly divergently arranged shock absorbing mechanisms, one on each side of said centrally disposed shock absorbing mechanism; and means for operating all of said mechanisms simultaneously from a draw bar, 85 said means including a longitudinally movable front follower having operative engagement with each of said three shock absorbing mechanisms.

8. In car construction, the combination with an underframe including, a bolster, an end sill, longitudinally extending centrally disposed draft sills, and diagonally extending, spaced draft sills on each side of said central draft sills; of a centrally disposed 100 shock absorbing mechanism, between said central draft sills; and diagonally extending shock absorbing mechanisms between said diagonally extending draft sills.

9. In car construction, the combination with an underframe end casting comprising, a bolster, an end sill, side sills, longitudinally extending draft sills, and diagonally extending draft sills, said casting being provided with rearwardly facing front stop 105 shoulders; of a front follower cooperable with said stop shoulders; a centrally disposed shock absorbing mechanism between said longitudinally extending draft sills; and diagonally extending shock absorbing mechanism between the respective diagonally extending draft sills, each of said shock absorbing mechanisms having operative engagement with said follower.

10. In car construction, the combination with an underframe end casting comprising, a bolster, an end sill, side sills, longitudinally extending draft sills, and diagonally extending draft sills, said casting being provided with rearwardly facing front stop 110 shoulders; of a front follower cooperable with said stop shoulders; a centrally disposed shock absorbing mechanism between said longitudinally extending draft sills; diagonally extending shock absorbing mecha- 125

- nisms between the respective diagonally extending draft sills, each of said shock absorbing mechanisms having operative engagement with said follower; a draw bar; and
5 a yoke connected to said draw bar encircling said follower and said centrally disposed shock absorbing mechanism and adapted to actuate the latter upon draft movement of the draw bar.
- 10 11. In car construction, the combination with a plurality of shock absorbing mechanisms; of means independently engaging

each shock absorbing mechanism for operating all of said shock absorbing mechanisms upon buffing movement of a draw bar; and means for operating only one of said mechanisms upon draft movement of the draw bar.

In witness that I claim the foregoing I have hereunto subscribed my name this first day of August, 1921.

WILLIAM J. BOHAN.
